FLANGE BENDING APPARATUS

Ussury A. Bartee, San Pablo, Calif.

Application June 15, 1942, Serial No. 447,136

2 Claims. (Cl. 153—28)

My invention relates to flanging apparatus, and more particularly to apparatus for the bending of flanges of channel beams.

In the application of channel beams to certain uses, it is found necessary to bend one or both of the flanges inwardly or outwardly out of their normal perpendicular relationship to the intermediate or floor section of the beam, and the angle to which the flange is to be bent is often somewhat critical.

In accordance with prior practice, such bending of the flanges is accomplished in a hit or miss fashion by applying a wrench to the flange at successive intervals as a beam is drawn from a pre-heating furnace. Accuracy depends in large measure upon the skill of the operator, and factors quite beyond his control often leave the flange and floor section distorted and irregular.

Among the objects of my invention are—

(1) To provide a novel and improved apparatus for the bending of flanges, which shall permit of a high degree of accuracy and uniformity in results, and without the use of skilled labor;

(2) To provide a novel and improved apparatus for the bending of flanges, which will preclude buckling or distortion in the finished product, and

(3) To provide a novel and improved apparatus for the bending of flanges, which is simple in structure yet rugged and dependable in use.

Additional objects will be brought out in the following description of my invention taken in conjunction with the accompanying drawings where-

in—

Figure 1 is a front elevational view of a preferred embodiment of my invention;

Figure 2 is a plan view of the same;

Figure 3 is an end view in the direction indicated by the arrow in Figure 1; and

Figure 4 is a view in section, taken on the line 4—4 of Figure 2.

Referring to the drawings for a detailed description of the invention, I provide an assembly comprising a yoke 5 including a pair of converging legs 7 joined by an intermediate section or cross-bar 9. Adjacent the extremity of each leg and normal thereto, there is affixed a short inwardly directed shaft 11 for rotatably carrying a frusto-conical shaped bending roller 13. The rollers are disposed with their smaller ends toward each other, and the spacing of the yoke legs is such as to provide spacing between the conical surfaces of the rollers, approximately the thickness of a flange at their point of closest approach. A handle 15 is attached to the center of the intermediate

section of the yoke. The yoke and roller assembly is supported between a pair of arcuate or semi-circular guides 17 which are disposed in parallel relationship to each other and anchored at their ends to base plates 19 by welding or other suitable anchoring means. A section of each guide, to one side of the center thereof, has a slot 21 formed therein, to receive a guide pin 23 which passes through the center of the intermediate section of the yoke. This permits adjustment of the angular position of the yoke and roller assembly in accordance with the angle to which a flange is to be bent. In employing the apparatus thus far described, for the purpose for which the apparatus is intended, the yoke and roller assembly is first shifted to a substantially vertical position, and a beam 25, as it is withdrawn from the pre-heating furnace, is caused to travel under the arcuate guides, with the front end of one of the flanges 27 engaging between the frusto-conical shaped rollers, at a point substantially coinciding with the center of curvature of the arcuate guides. An operator grasps the handle and swings the yoke through the desired angle to which the flange is to be bent from its normal vertical position, and the yoke is thereafter held in that position while the entire beam is withdrawn from the furnace. An accurate indication of the angle may be determined by suitable markings 29 on the arcuate guides along the slotted portion thereof.

To assure the desired angle of bend, when the direction of bend is outward, it is essential that the beam be maintained in surface contact with the floor over which it is being pulled, to avoid tilting of the beam, and to this end, I provide a hold-down roller 31 on a shaft 33 supported between a pair of supporting bars 35 anchored between the arcuate guides. These bars will necessarily be disposed at an angle to provide sufficient clearance with respect to the adjustment range of the yoke 5, and to permit such angular disposition of the supporting bars, the hold-down roller, like the flanging rollers, will be frusto-conical in shape. The vertical thrust against this roller, caused by the tendency of the beam to tilt under the bending force of the yoke and roller assembly on the flange, may be taken up by a brace bar 37 anchored between the arcuate guides 17 and welded at its lower end to the upper supporting bar for the hold-down roller.

The outward bending effect on the beam flange has a tendency to produce a roll or buckle in the floor section of the beam adjacent the flange, and to avoid such distortion, the hold-down roller 31 is preferably mounted so as to engage the

beam as close to the flange as possible, and is of sufficient thickness to engage a substantial portion of the floor section of the beam.

It will be realized that the yoke and roller assembly, when put in operation, will be exposed to heavy twisting and bending strains and stresses, and to realize a proper and uniform bend of the flange, it is quite essential that the normal spacing between the bending rollers shall be maintained. Accordingly, I provide a tie block 39 between the bending rollers 13, and into this block, I screw-thread the roller shafts 11. This tie block serves to resist any tendency on the part of the rollers 13 to spread during use. Additional rigidification of the assembly is realized by a reinforcing and bracing frame 41 of rectangular shape, whose side members 43 are welded or otherwise suitably attached at their middle to the outer sides of the yoke legs 7. The frame snugly fits in sliding engagement between a pair of spaced reinforced cross-beams 45, these cross-beams being supported at their ends by suitable angle iron posts 47 mounted on the base plates 19 and braced by suitable angularly disposed bracing members 49.

The distorting or twisting thrust applied to the bending rollers 13 during use of the apparatus, is taken up by a pair of thrust neutralizing rollers 51 supported on depending shafts 53 from a cross-bar 55 preferably welded between the legs of the yoke. These thrust neutralizing rollers are partly cylindrical and partly conical, and contact each other along their cylindrical surfaces while engaging the bending rollers 13 with their conical surfaces. To take up for wear or play between the various elements and thereby assure proper engagement between the thrust neutralizing rollers and the bending rollers, the thrust neutralizing rollers could be adjustably mounted in this cross-bar 55 by extending the shafts of these rollers through the intermediate section of the yoke in threaded engagement therewith.

The hold-down roller 31 may be suitably braced against side thrust by a bar 57 welded to the upper supporting bar for the hold-down roller, and extending to and engaging the reinforced cross-beams 45 to which it may preferably be welded.

The apparatus thus described is capable of efficiently producing the desired angle of bend in the flange of a channel beam, with high efficiency and considerable uniformity of results. Guess-work is no longer a factor, since it is only necessary for an operator to swing the yoke through the desired angle and hold it in that one position.

Best results are obtained by so disposing the bending rollers 13 that the rollers engage the flange and hold such engagement at the lowest point on either side thereof. To fulfill this relationship, the conical surfaces of the bending roller engaging the outer surface of the flange, must be slightly lower in the direction of the floor, than the other. This relationship may be realized by utilizing a slightly larger bending roller on that side which engages the outer surface of the flange, or a roller of the same size as the other may be employed, in which case the supporting shaft for that roller will be mounted at a slightly greater distance down the yoke leg from the intermediate section of the yoke. In such case, the cross-bar 55 which sup-

ports the thrust neutralization rollers, will have to be lowered slightly at one end in the direction of the outside roller to effect operative engagement therewith between the thrust neutralization roller and its associated bending roller.

The apparatus has been illustrated in the process of producing an outward bend of the flange. To utilize the same apparatus in the operation of producing an inward bend of a flange, 10 the pin 23 may be removed and the yoke and roller assembly reversed so that the lower bending roller will be on the left, instead of the right as viewed in Figure 1. With the machine thus 15 adjusted, the beam will be drawn from the furnace so that its left flange will travel approximately under the center of the arcuate guides of the apparatus for engagement between the bending rollers. When thus engaged, the yoke will be adjusted to the desired angle in the same 20 direction as previously, whereby the proper angle of bend inwardly will be realized. Under these conditions, the channel beam will be located out of the region of the hold-down roller 31, but in as much as there will be no tendency toward 25 tilting of the beam under conditions for producing an inward bend of a flange, the hold-down roller is not necessary.

It will be apparent from the above description of my invention, that the same will fulfill the 30 objects set forth previously, and while I have disclosed a preferred embodiment thereof in detail, it will be apparent that the same is subject to alteration and modification, without departing from the spirit of the invention. I, accordingly, 35 do not desire to be limited in my protection to the specific details of the preferred embodiment described by me, except as may be necessitated by the appended claims.

I claim:

1. Apparatus for bending the flanges of channel beams comprising, an assembly including a yoke having an intermediate section and legs extending from the extremities thereof and converging toward each other, an inwardly directed 40 shaft adjacent the end of each of said legs, a frusto-conical roller mounted on each of said shafts with the conical surfaces of said rollers facing each other and spaced approximately the thickness of a flange at their point of closest approach, a tie block connecting the inner ends of said shafts, and a handle operatively connected to said yoke.

2. Apparatus for bending the flanges of channel beams comprising, an assembly including a yoke having an intermediate section and legs extending from the extremities thereof and converging toward each other, a frusto-conical roller 45 rotatably mounted on each leg adjacent the free end thereof with the conical surfaces of said rollers facing each other and spaced approximately the thickness of a flange at their point of closest approach, a cross-bar connected between the legs of said yoke at a location above said rollers, a pair of thrust neutralization rollers supported by said cross-bar in engagement with each other and with said first rollers, a handle 50 operatively connected to said yoke, and means rigidifying said assembly to absorb strains and stresses developed during the bending of a flange.

USSURY A. BARTEE.
